(57) **CLAIM**

The ornamental design for a vending machine, as shown and described.

DESCRIPTION

FIG. 1: is a front perspective view of the vending machine.

FIG. 2: is a front elevation view thereof.

FIG. 3: is a rear elevation view thereof.

FIG. 4: is a left side elevation view thereof.

FIG. 5: is a right side elevation view thereof.

FIG. 6: is a top plan view thereof; and,

FIG. 7: is a bottom plan view thereof.

The broken lines shown in the drawings illustrate portions of the vending machine that form no part of the claimed design.
